(57) **CLAIM**

The ornamental design for a polygonal, slip-jointed hybrid electrical pole, as shown and described.

DESCRIPTION

FIG. 1 is a perspective view of a polygonal, slip-jointed hybrid electrical pole showing our new design;

FIG. 2 is a side elevational view thereof;

FIG. 3 is the opposite side elevational view thereof;

FIG. 4 is a top plan view thereof;

FIG. 5 is a bottom plan view thereof;

FIG. 6 is a perspective view of a second embodiment of a polygonal, slip-jointed hybrid electrical pole showing our new design;

FIG. 7 is a side elevational view thereof;

FIG. 8 is the opposite side elevational view thereof;

FIG. 9 is a bottom plan view thereof;

FIG. 10 is a perspective view of a third embodiment of a polygonal, slip-jointed hybrid electrical pole showing our new design;

FIG. 11 is a side elevational view thereof;

FIG. 12 is the opposite side elevational view thereof; and,

FIG. 13 is a bottom plan view thereof.

The broken lines are for illustrative purposes only and form no part of the claimed design.
